UNITED STATES PATENT OFFICE

2,487,131

COMBINATION ASH AND CIGARETTE
RECEPTACLE

Clinton L. Harris, Rushsylvania, Ohio

Application December 31, 1947, Serial No. 794,968

2 Claims. (Cl. 206—38)

1

This invention relates to new and useful improvements in cigarette containers and the primary object of the present invention is to provide a novel and improved combination ash and cigarette receptacle.

Another important object of the present invention is to provide a combination ash and cigarette receptacle including an ash receiving compartment having a receiving opening and embodying novel and improved means for conducting ashes from the opening to the bottom of the ash receiving compartment, in such a manner as to reduce the normal dust prevalent when the ashes engage the bottom wall of the compartment.

A further object of the present invention is to provide a combination ash and cigarette receptacle that includes an ash receiving compartment, a cigarette receiving compartment, and novel and improved slidable closure means for removing ashes from the ash compartment.

A still further aim of the present invention is to provide a combination ash and cigarette receptacle that is simple and practical in construction, small and compact in structure, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the combination ash and cigarette receptacle constructed in accordance with the present invention, and with parts thereof broken away and shown in sections;

Figure 2 is a transverse horizontal sectional view of the present receptacle taken substantially on the plane of section line 2—2 of Figure 1;

Figure 3 is a longitudinal vertical sectional view of the present receptacle taken substantially on the plane of section line 3—3 of Figure 1;

Figure 4 is a longitudinal vertical sectional view of the present receptacle taken substantially on the plane of section line 4—4 of Figure 1; and,

Figure 5 is a fragmentary bottom plan view of the present receptacle and showing in dotted lines the ash receiving compartment slidable closure in an open position.

Referring now to the drawings in detail, wherein for the purpose of illustration, there is dis-

2

closed a preferred embodiment of the present invention, the numeral 10 represents a substantially rectangular case generally, having spaced parallel side walls 12, spaced parallel end walls 14 and 16, and a bottom wall 20. The upper edges 22 of the walls 12 and 14 are provided with reduced, upstanding flanges 24 that frictionally engage notches or grooves 26 provided in the end wall 20 and side walls 30 of a closure 32 which includes a further end wall 34 that is hinged as at 36 to the end wall 14. Fixed to the closure 32, is a substantially L-shaped spring arm 38 having an arcuated end portion 40 that frictionally engages a protuberance 42 provided on the end wall 16, for holding the closure 32 in a normally closed position relative to the case 10.

Fixedly secured to opposing inner faces of the side walls 12, and spaced relative to the end wall 14, is a substantially rectangular partition 44 that divides the case 10 in a cigarette receiving compartment 46 and an ash receiving compartment 48. The upper end of the ash receiving compartment 48 is closed by a rigid closure plate 50 that will prevent ashes deposited within the ash receiving compartment 48 from entering the cigarette receiving compartment 46, to harmfully effect cigarettes placed in the latter of said compartments.

In order to facilitate the placement of cigarette ashes in the ash receiving compartment 48, there is provided a substantially rectangular opening 52 in one of the side walls 12 of the case 10 that communicates with the compartment 48.

The bottom 20 of the case 10 is provided with a discharge opening 54 that communicates with the ash receiving compartment 48 and this opening 54 is provided with longitudinal guide grooves 56 that slidably engage the reduced longitudinal side edges 58 of a removable closure 60, the outer face of which is coplanar with the face of the bottom wall 20. The closure 60 is provided with a finger engaging notch 62 in its outer face, and a protuberance or stop 64 on its inner face that frictionally engages the inner face of the end wall 14, for normally locking the closure in a closed position relative to the opening 54.

Rigidly secured to the inner face of one of the side walls 12, are the flanged portions 66 and 68 of an upper baffle plate 70 and a lower baffle plate 72 that incline downwardly and are spaced relative to the other side wall of the case 10 to which there is secured the flange portion 74 of an intermediate downwardly inclined baffle plate

76 which inclines downwardly toward and is spaced from the lower baffle plate 72.

In practical use of the device, when the ashes are deposited in the opening 52, the same will engage the upper baffle plate 70, slide downwardly on the upper baffle plate 70 to engage the intermediate baffle plate 76, slide downwardly on the baffle plate 76 to engage the lower baffle plate 72 and hence the ashes will pass into the lower portion of the compartment 48 where they may be removed by opening the closure 60.

Obviously, by using the baffle plates to reduce the normal gravitational descent of the ashes in the compartment 48, the amount of dust emitted from the compartment 48 will be retained at a minimum. Also, the baffle plates will prevent the ashes from passing from the compartment 48 outwardly through the opening 52.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A combination ash and cigarette receptacle comprising a case having a bottom wall and a hinged upper wall, a partition fixed in said case

and dividing the same into an ash compartment and a cigarette compartment, a closure plate closing the upper end of said ash compartment, an ash receiving opening provided in said case adjacent said upper wall and communicating with the ash compartment, a plurality of inclined baffle plates mounted in said ash compartment arranged to prevent ashes from passing outwardly through the ash receiving opening, and including spaced parallel upper and lower baffles and an intermediate baffle, said intermediate baffle being inclined in an opposite direction than said upper and lower baffles, an opening provided in the bottom wall of said case having side edges, grooves provided in the side edges of said last-mentioned opening, a closure having side edges slidably received in said grooves, and means carried by and locking last-mentioned closure in a closed position.

2. The combination of claim 1 wherein said last-mentioned means includes a protuberance on the inner face of said closure, said case having an end wall including a lower edge forming an abutment for said protuberance.

CLINTON L. HARRIS.
